United States Patent Office

Des. 221,834
Patented Sept. 14, 1971

221,834

BOTTLE

Ira W. Schwartz, Great Neck, N.Y., assignor to National
Distillers and Chemical Corporation, New York, N.Y.

Filed June 10, 1970, Ser. No. 23,411

Term of patent 14 years

Int. Cl. D9—01

U.S. Cl. D9—48

FIG. 1

FIG. 2

FIG. 3

FIG. 5

FIG. 1 is a side elevational view of a bottle illustrating my new design;

FIG. 2 is a top plan view thereof;

FIG. 3 is a bottom plan view thereof;

FIG. 4 is an exploded front elevational view thereof showing the cap removed from the bottle; and

FIG. 5 is a rear elevational view thereof.

I claim:

The ornamental design for a bottle, as shown.
